UNITED STATES PATENT OFFICE.

AXEL SAMUEL VOGT, OF ALTOONA, PENNSYLVANIA, ASSIGNOR TO COALE MUFFLER AND SAFETY VALVE COMPANY, OF BALTIMORE, MARYLAND, A CORPORATION OF NEW JERSEY.

VALVE-CLAMP.

1,087,337.

Specification of Letters Patent. Patented Feb. 17, 1914.

Application filed March 14, 1913. Serial No. 754,198.

To all whom it may concern:

Be it known that I, AXEL S. VOGT, a subject of the King of Sweden, residing at Altoona, Blair county, State of Pennsylvania, have invented certain new and useful Improvements in Valve-Clamps, of which the following is a specification.

This invention relates to a clamp or tool for use in connection with safety valves and 10 particularly adapted to close the valve independently of the pressure regulating device of the valve when the boiler is being tested by hydraulic pressure.

The present regulations relating to the 15 use of steam boilers require frequent tests of safety valves, and compliance at these tests with certain standards of efficiency in the action of the valves, particularly that the valve shall pop at certain definite pressures 20 determined by the other features of the plant, as the pressure at which the boiler is to be used, etc. The regulations also require that steam boilers shall be tested by hydraulic pressure at regular intervals. The 25 pressures employed at such tests are of course higher than the steam pressure to which the boilers are normally subjected, and to maintain the pressure, the safety valve must be closed in some way to withstand 30 the testing pressure. This is accomplished in various ways, the most primitive of which is to screw down the valve and compress the spring until its tension is sufficient to withstand the hydraulic pressure. 35 When this method is employed it is exceedingly difficult to comply with the requirements for valve tests as the parts are not only thrown out of adjustment, which might be regained by marking them and returning 40 them to their original position, but also the spring is distorted so that when the adjusting screw is returned to its original position, the pressure at which the valve pops is not the same as the one to which it was 45 previously adjusted. Another serious objection to this practice is that the attendant is apt to lose sight of the fact that the adjustment of the safety valve has been changed and neglect to re-adjust it. Various disastrous 50 results have followed such oversights.

To avoid the necessity for re-adjusting the valve and also to prevent injury to the valve in testing the boiler, various engineers have adopted the practice of removing the

valve bodily from its position on the boiler 55 and closing the aperture by means of a screw cap or plug. To thus remove the valve is expensive and undesirable, for the steam-tight joint which has been established between the valve base and the boiler connection is broken, and to replace the valve and establish a tight joint involves considerable expense of time and effort.

The device of the present invention is constructed with a view to overcoming the various difficulties described. It is independent 65 of the valve spring and serves to positively clamp or lock the valve on its seat. Further, it is so constructed that it may be applied and removed from the valve without 70 in any way disturbing the adjustment, and when it is in operation, distortion of the spring from any cause is impossible.

The clamp or lock includes a member 75 adapted to be passed through the valve casting to engage the valve proper and hold it on its seat, together with an external clamp for holding the internal member in position. This latter member is of dimensions sufficient to attract the attention of any casual 80 observer, so that its presence on the valve cannot be ignored and the chance that the lock or clamp may be left on the valve by any ordinary inadvertence on the part of the attendant is so small that it may be considered negligible.

The various safety valves in common use are constructed with an adjusting screw or bolt in the center of the cap by means of which the tension of the spring is adjusted. 90 This bolt may be provided with a central aperture extending its full length, through which a portion of the steam released by the valve escapes. In the case of valves which are not provided with such an aperture it 95 will be easily understood that one can be bored at a comparatively slight cost. In the device of the invention a vertical pin or rod is passed downward preferably through this aperture in the direction of the 100 axis of the valve and forced at its lower end against the top of the valve or some member, bearing directly thereon, so that the rod serves to hold the valve positively against its seat. Near its upper end the rod is threaded and 105 passed through a correspondingly threaded aperture in the body, nut or shank member of the clamp, which in turn is provided with

suitable means as jaws for gripping the head of the adjusting screw or any other available support. The body member may have a hand lever by which it can be held to prevent rotation, and the screw is provided with a suitable cross arm by means of which it may be turned to apply to the rod the necessary thrust to force it down and hold the valve rigidly on its seat. The hand lever, etc., should be of considerable dimensions and formed to make the device as conspicuous as possible to the end that it shall not be overlooked when steam is to be gotten up.

The accompanying drawings illustrate a safety valve to which a lock or clamp, constructed in accordance with my invention, has been applied.

Figure 1 is a vertical, central cross-section through the valve and the body of the clamp 20 showing the jaws, lever, etc. in elevation. Fig. 2 is an elevation of the clamp looking from the left in Fig. 1. Fig. 3 is a plan of the clamp.

Referring to the drawings by numerals, 25 each of which indicates the same or equivalent parts in the different figures, the safety valve illustrated consists of a valve proper 1 engaging a seat 2, the valve being normally held in its seat by means of a spring 3, the 30 tension of which is adjusted by means of a screw or screw plug 4 engaging a threaded aperture 5 in the casing and the term "safety valve", as used herein, refers to this or an equivalent structure. The term "valve 35 proper" refers to any member having the prime function of applicant's member 1, i. e., which serves to close the valve or seat opening in a safety valve. The plug has a central, axial aperture 6 through which is 40 passed the thrust rod 7 of the locking or clamping device to be described. This consists of a nut or body member 8 with which the rod 7 has a threaded engagement, the latter being threaded at 9 to engage corresponding threads 10 in the aperture 11 in 45 the body or nut 8, and the latter is provided with a radially-placed arm or hand lever 12 which may be manually engaged by the operator to prevent rotation of the nut as the 50 thrust rod is turned to apply the necessary pressure to the valve as hereinafter described. To take up the re-action of the thrust applied to the valve, the nut is suitably supported as by hinged jaws 13 pivoted at 14 in slots 15 provided to receive the jaws, and the latter are suitably notched or toothed at 16 at their lower extremities to engage the square head 17 on the upper end of the adjusting screw. It will be noted 55 that when the jaws are in engagement with the nut, as shown, the upper, inner faces of the jaw levers are inclined upward and outward, that is, they diverge, and to hold the jaws in operative position, as shown, any 60 suitable means as the collar 18 is provided.

This encircles the rod 7 near its upper end, sliding up and down and is adapted to enter the space between the upper ends of the jaws to hold them in operative position, as shown, at the will of the operator. To turn 70 the rod and move it relatively to the nut 8 and apply the necessary thrust to the rod and force it downward against the valve to lock the latter in position, it is provided at its upper end with a convenient grip shown 75 in the form of a cross arm 19.

The operation of the device will be apparent from the description taken in connection with the drawings.

When a test of the boiler is to be made 80 and it is therefore found advisable to lock the valve, the clamp, being in approximate adjustment, is placed in position on the screw or bolt 4, the rod 7 being thrust downward through the axial aperture 6 therein. The head 17 of the adjusting screw is engaged by the jaws 13, the teeth 16 of which are passed under the lower flat surface of the head. In this position of the jaws the collar 18 is slid downward between their upper extremities, locking them in position. Then the lever 12 being held in one hand, the rod 7 is turned by means of the cross-bar 19 until the rod is forced downward against the valve or the saddle 20 thereon. When the device becomes rigid so that the screw refuses to turn under ordinary pressure, the valve is locked. Any sort of pressure test to which the boiler may be subjected can then be carried on without danger 90 of injury to the valve or variation of the adjustment, and when the test is finished, the clamp can be conveniently removed by reversing the operation described, first loosening the rod 7 by a turn or so of the cross-bar 19 and rod 7, then raising the collar 18 so that the jaws 13 are released, following which the clamp may be raised, lifting the rod from the aperture in the screw. It is 95 apparent that in this way the valve is clamped and released without in any way disturbing its adjustment or varying the tension of the spring, and that it may thus be locked against possibility of opening under any probable testing pressure. Thus removal of the valve or changing the adjustment for this purpose is rendered entirely 100 unnecessary.

An important feature of the device is that the external body of the clamp, which is always in view of the attendant, is so constructed that it is easily apparent so that no experienced person in charge of the plant could by any possibility overlook it and inadvertently leave the valve clamped when 105 the boiler is under steam.

I have thus described specifically a single embodiment of my invention in order that its nature and operation may be clearly understood. However, the specific terms here- 110 115 120 125 130

in are used in their descriptive rather than in their limiting sense and the scope of the invention is defined in the claims:

I claim—

5 1. In combination with a safety valve having a valve proper, means for use in boiler tests and the like for positively locking the valve proper on its seat, the same consisting of a rigid member independent of 10 the valve proper, and means for rigidly supporting said member in contact with the outer side of the valve proper.

15 2. In combination with a safety valve having a valve proper, a valve seat, a spring, and means for adjusting the same, means independent of the spring for positively locking the valve proper on its seat.

20 3. In combination with a safety valve having a valve proper, a valve seat, a spring, and means for adjusting the same, means independent of the spring in the form of a vertical thrust rod for positively locking the valve proper on its seat and means for holding the rod rigidly in position at one 25 end resting on the valve proper.

4. In combination with a safety valve having an adjusting screw with an aperture therein a valve proper, means for locking the valve proper on its seat consisting of an 30 upright rod extending through the aperture and engaging the valve proper, and means for applying thrust to the rod and holding it under compression.

35 5. In combination with a safety valve having an adjusting screw with an aperture therein and a valve proper, means for locking the valve proper on its seat consisting of a rod extending downward through the aperture toward the valve proper and means 40 for forcing the rod downward and holding the valve proper on its seat consisting of a nut having a threaded engagement with the

rod, an arm by which the nut may be held to prevent rotation, swinging jaws on the nut for holding the nut in fixed relation 45 to the valve casing, means for holding the jaws in operative position, and means on the rod whereby it may be engaged to rotate it.

6. In combination with a safety valve having an adjusting screw with an aperture 50 therein a valve proper, means for locking the valve proper on its seat consisting of an upright rod extending through the aperture, and means for forcing the rod downward to hold the valve proper on its seat consisting 55 of a nut having a threaded engagement with the rod, means for holding the nut in fixed relation to the safety valve frame, and means on the rod by which it may be engaged to rotate it. 60

7. In combination with a safety valve having a valve proper an aperture extending in the direction of the throw of the valve proper, a rod having an aperture disposed in the direction of the throw of the valve proper, a rod extending through the aperture, and means for forcing the rod against the valve proper, thereby placing and holding the rod under compression and locking the valve proper on its seat. 65

8. A clamp for safety valves consisting of a conspicuous, external member, and means controlled thereby extending within the valve casing and engaging the valve proper the said means being in the form of a rigid 70 member bearing on the valve proper and means for supporting said member. 75

Signed by me at Altoona, Pennsylvania, this 26th day of February, 1913.
